UNITED STATES PATENT OFFICE.

JOHN F. KELLEY, OF TUSCALOOSA, ALABAMA.

ICE CAN.

Application filed December 27, 1924. Serial No. 758,372.

To all whom it may concern:

Be it known that I, JOHN F. KELLEY, a citizen of the United States, and resident of Tuscaloosa, in the county of Tuscaloosa and 5 State of Alabama, have invented certain new and useful Improvements in Ice Cans, of which the following is a specification.

My invention relates to improvements in cans such as are commonly employed in the 10 manufacture of block ice, my purpose being to provide an improved can construction whereby artificial block ice may be produced without the usual soft central core in a minimum amount of time and by the expenditure of a minimum amount of energy.

With the foregoing and other purposes in view my invention consists in the novel features of construction, combination and arrangement of parts as will be hereinafter 15 more fully described, illustrated in the accompanying drawings and defined in the appended claims.

In the drawings, wherein like characters of reference denote corresponding parts in 20 the different views:—

Figure 1 is a central longitudinal section through a can constructed in accordance with my invention;

Figure 2, a central transverse section; and 25 Figure 3, a horizontal section.

Referring to the drawings in detail, it will be observed that my improved can is elongated and of rectangular shape in cross section, being composed of two sides 10, 10, 30 two ends 11, 11 and a bottom 12.

The sides 10, 10 are of slightly greater width at their tops than at their bottoms, so that can flares outwardly from its bottom towards its top to facilitate removal 35 of a block of ice formed therein. The ends 11, 11 on the other hand are in the present instance of the same width throughout their length, although they may be formed of greater width at their tops than at their bottoms similarly to the sides 10, 10.

Essentially, however, each end is provided with a central inward extension 13 running the full length of the can and tapered inwardly to a rounded inner end as clearly shown in 45 Figure 3, said extensions being of any depth desired and, as clearly shown in Figures 1 and 2, they also are tapered in depth as well as width from the bottom of the can towards its top.

The bottom 12 fits within the sides and ends 10, 10 and 11, 11, respectively, and is

cut out at its ends to receive the lower extremities of the inward extensions 13, 13, a downturned flange 14 on said bottom fitting against the sides and ends of the can 60 as well as against the lower extremities of said inward extensions 13, 13 and being riveted or otherwise secured in place as indicated at 15. The tapered formation of the extensions 13, 13 in conjunction with the 65 flared formation of the sides of the can provides for easy removal of a block of ice from the can as is manifest.

Around the top of the can is riveted or otherwise secured a band 16 which enhances 70 the rigidity of the structure and provides a means of lowering the can into and lifting it from the brine in which it is adapted to be immersed to effect freezing of its contents.

It has been found in practice that a block of ice frozen in a can constructed as described is free from the soft central core usually found in blocks of manufactured ice and that the freezing operation requires materially less time and power than has been required heretofore to freeze a block of ice of the same size, the reason being that the extensions 13, 13 admit the brine to the central portion of the can so that freezing occurs here substantially at the same rate as at the edges of the can, whereas in prior can constructions freezing occurs first at the edges of the can and progresses towards the center of the can with the resultant formation of a soft central core as aforementioned.

From the foregoing description considered in connection with the accompanying drawings, it is believed that the construction and advantages of my improved can will be fully understood. It is desired to point out, however, that various changes and desirable additions may be made in and to the structure shown within the spirit and scope of my invention as defined in the appended claims.

I claim:

In ice manufacturing apparatus, a can adapted to be placed in a freezing medium, said can having opposite walls thereof provided with outwardly opening hollow ribs running the full length thereof, each of said hollow ribs extending into the can a distance approximately equal to one-fourth of the distance between the walls having said ribs 105 and being spaced from the adjacent side walls of the can a distance approximately 110

equal to the distance that said ribs extend into the can so that water within and at the center of the can will be frozen at substantially the same rate as at the sides of the can, said ribs being tapered from their lower towards their upper ends and also being tapered inwardly, said can having a bottom provided with recesses through which the lower ends of said hollow ribs extend where-
10 by said ribs open through the bottom as well as the sides of the can to permit free

circulation of the cooling medium there-
through, and downturned flanges on said bottom about the recesses therein, embrac-
ing and secured to said ribs to stiffen the
latter and to provide a means of producing
a water tight joint between the sides and
bottom. ¹⁵

In testimony whereof I hereunto affix my signature.

JOHN F. KELLEY.
